161,617

SEWING MATERIAL HOLDER

Jack P. Faeder, Beverly Hills, Calif.

Application July 3, 1950, Serial No. 10,949

Term of patent 14 years

(Cl. D3—19)

To all whom it may concern:

Be it known that I, Jack P. Faeder, a citizen of the United States and a resident of the city of Beverly Hills, in the county of Los Angeles and State of California, have invented a new, original, and ornamental Design for Sewing Material Holder, of which the following is a specification, reference being had to the accompanying drawing, forming part thereof, in which:

Fig. 1 is a perspective view of a sewing material holder, showing my new design;

Fig. 2 is a rear elevational view; and

Fig. 3 is a plan view thereof.

I claim:

The ornamental design for a sewing material holder, as shown.

JACK P. FAEDER.
